PROCESS AND APPARATUS FOR CONVERTING HYDROCARBON OILS

Original Filed March 12, 1920

UNITED STATES PATENT OFFICE

LESTER KIRSCHBRAUN, OF LEONIA, NEW JERSEY, ASSIGNOR TO UNIVERSAL OIL PRODUCTS COMPANY, OF CHICAGO, ILLINOIS, A CORPORATION OF SOUTH DAKOTA

PROCESS AND APPARATUS FOR CONVERTING HYDROCARBON OILS

Application filed March 12, 1920, Serial No. 365,259. Renewed September 26, 1928.

This application is an improvement of my application, Serial No. 350,752, filed January 12, 1920.

This invention relates to a process and apparatus for converting hydrocarbons and refers more particularly to a process in which high boiling point hydrocarbons are converted into hydrocarbons of a lower boiling point such as gasoline and the like.

10 Among its salient objects are to provide a process in which the oil vapors cracked from the body of the oil are dephlegmated and subjected to a condensing action by being passed through the incoming raw oil and intermingled in intimate relation therewith, providing at the same time an economical and effective interchanging of heat, a process in which the reflux distillate is combined with the raw oil and charged to the cracking zone to be retreated; to provide a process 15 in which any substantial collection of precipitated carbon in the cracking tubes is obviated and an apparatus particularly adapted to the cleaning of this collected carbon; to provide a process in which the oil is heated in substantially solid vertical streams and 20 circulated in a course opposed to that of the heating gases; to provide a process in which differential pressures are maintained on the oil in various parts of the system; to provide an improved and novel type of apparatus for carrying out the process and in general to provide a process and apparatus of the character referred to.

35 In the single figure the apparatus is diagrammatically shown, partly in section and with parts broken away.

Referring to the drawing, within the furnace 1 is mounted a series of vertical cracking tubes 2, which are connected at the top and bottom by drums 3 and 4. The upper drum 3 is divided into two chambers by means of partition wall 5. The heating gases from the furnace pass in the direction 40 shown by the arrows over the heating tubes and out through the stack 6. The oil charge is drawn from any suitable source of supply (not shown) and charged into the top of the dephlegmator 7 through the charging pipe 8, pump 9 and line 10. Valves 11 and

12 control lines 10 and 8 respectively. The raw oil passing down through the dephlegmator is brought into intimate contact with the gaseous vapors which are passing in an opposite direction. The oil coursing down through the dephlegmator stands at a height in the respective chambers of the dephlegmator denoted by the dotted lines shown at 12'. This height is regulated by stand pipes 13 through which the oil passes 55 from one chamber to another. The oil vapors rising through the dephlegmator through risers 14 are caused to bubble up through the standing oil due to the deflectors 15. The raw oil, together with the reflux 60 condensate, collects in the bottom of the dephlegmator and passes down through the line 16 controlled by valve 17 to a pump 18. This pump forces the oil and distillate through the feed line 19 to the upper chamber 3a of the drum 3. The oil then courses 65 down through the vertical cracking tubes in the direction shown by the arrows into the bottom drum 4 and up through similar cracking tubes connected to the lower drum and 70 opposite chamber 3b of the upper drum. 75

It will be noted that the oil charge travels in a direction opposed to the course of the heating gases. From the top of the chamber 3b, a gooseneck 20, controlled by valve 21, directs the heated oil to the vapor chamber 22. A residuum drawoff 23 regulated by a valve 24 is tapped into the lower part of this vapor chamber. The vapors from the vapor chamber pass through the line 25 controlled 80 by valve 26 to the dephlegmator 7 and rise, as previously explained, through the raw oil charge. The vapors which are not condensed in the dephlegmator pass off to a water condenser 27 through the line 28, the latter being 85 controlled by a valve 29. The condensed distillate is collected in a receiver 30, which is supplied with a suitable drawoff 31 regulated by a valve 32. The receiver has a liquid gauge 33, pressure gauge 34 and a pressure 90 relief pipe 35 controlled by a valve 36. In the bottom drum 4, which is part of the cracking zone, are supplied two large cleaning plates 37, which are easily removable and furnish an accessible means of removing the 95 100

precipitated carbon from the cracking zone, as a greater part of the carbon will collect in the lower drum due to the vertical position of the cracking tube. A similar cleaning 5 plate 38 makes the chamber 3b accessible for cleaning. The end plates 39 and 40 of the vapor chamber 22 are removable for cleaning of the vapor chamber. It is understood that the system is equipped with the usual pressure 10 gauges, pyrometers and sight feeds. The object of interposing the valves 21, 26 and 29 in the lines 20, 25 and 28 respectively, is for the purpose of operating the system under differential pressures if desired. By 15 this I mean, the cracking zone may be maintained under one pressure while the vapor chamber and dephlegmator are maintained under lower pressures regulated by these valves. In this manner, a more effective 20 cracking and vaporization of the hydrocarbon oils may be obtained. Also conditions of pressure may be altered more readily within the system during its operation and consequently, an increased yield of lower boiling 25 point hydrocarbons obtained.

In the construction here shown, I have mounted the vapor chamber somewhat higher than in my former application, decreasing the amount of precipitated carbon 30 which will form in the vapor chamber as the precipitated carbon and distillate which condenses directly on leaving the cracking zone will flow back through the gooseneck 20 into the cracking zone and collect in the lower 35 drum 4, from which it can be easily cleaned.

The following illustrative run may be given: Taking gas oil of say, 32° to 34° Baumé from the mid-continent field, I subject the same to a temperature of from 750° 40 to 900° F., and a pressure of 100 lbs. to 150 lbs.; under such conditions a yield of from 35% to 40% of the original gas oil will be converted into lower boiling point hydrocarbons. The apparatus is preferably operated 45 as a continuous process.

I claim as my invention:

1. In an apparatus for converting hydrocarbons, the combination with a cracking zone mounted in a heating furnace comprising a plurality of vertically arranged cracking tubes connected by upper and lower drums, said upper drum being centrally divided into two chambers, of a charging line connected to one of the chambers of the upper drum, an oil transfer line connected to the opposite chamber of the upper drum, means for causing the heating gases to travel in a course opposed to the travel of the oil, an enlarged vapor chamber connected to said 50 oil transfer line, a dephlegmating means, comprising means for intermingling the incoming raw oils with the oil vapors connected to the vapor chamber, means for drawing off the raw oil and distillate from the 55 dephlegmating means and charging the same

to the cracking zone, means for condensing and collecting the vapors from the dephlegmating means, valves interposed in the vapor and liquid lines for maintaining successively lower pressures in the cracking zone, vapor 70 chamber, dephlegmator and condenser.

2. The process of converting hydrocarbon oils, comprising passing oil in a plurality of vertical streams first downwardly through a heating chamber maintained at cracking temperature, then passing the oil in a plurality of streams upwardly through said chamber, in discharging the oil and vapors after the downward and upward passage of the oil to an unheated expansion chamber, in taking off the vapors from the chamber, and in maintaining a lower pressure in the expansion chamber than in the heating chamber.

3. The process of converting hydrocarbon oils, comprising passing oil downwardly in a plurality of small vertical streams in a heating chamber, in then causing the oil to travel upwardly in a plurality of small vertical streams in the heating chamber in a course substantially opposite to the travel of heating gases passing through said chamber, heating the oil to cracking temperature during its travel through said chamber in discharging the oil into an enlarged vapor chamber, in removing vapors from said chamber, in discharging the vapors to a dephlegmator, in introducing raw oil to the dephlegmator to condense portions of the vapors, in discharging the uncondensed vapors, in collecting the condensate and raw oil, in introducing the same to the heating chamber, and in maintaining successively lower vapor pressures on the oil in the different units of the system.

4. A process of converting hydrocarbon oils consisting in passing the oil first downward in a plurality of small vertical streams, then upward in a plurality of small vertical streams through a cracking zone in a course opposed to the travel of the heating gases, directing the oil to an enlarged unheated reaction chamber, taking off the vapors from said chamber, and subjecting them to the condensing and dephlegmating action of being brought into intimate relation with a plurality of oil pools in a dephlegmator, continuously introducing raw oil to said dephlegmator, passing the uncondensed vapors to a condenser and receiver, and maintaining successively lower pressures upon the oil in the different parts of the system.

5. The process of converting higher boiling point hydrocarbon oils into lower boiling point hydrocarbon oils, which consists in passing oil in a plurality of substantially vertical streams first downwardly through a heating zone, then upwardly through said zone, the temperatures to which the oil is subjected in said zone being such as to cause sub- 125

stantial conversion of the oil, in discharging said oil into an expansion chamber, in taking off the vapors from the chamber, and maintaining the pressure in the expansion chamber lower than that to which the oil was subjected in passing through the cracking zone.

6. A process of converting hydrocarbon oils consisting in passing the oil first downward in a plurality of small vertical streams, then upward in a plurality of small vertical streams through a cracking zone in a course opposed to the travel of the heating gases, directing the oil to an enlarged unheated reaction chamber, taking off the vapors from said chamber, and subjecting them to the condensing and dephlegmating action of being brought into intimate relation with a plurality of oil pools in a dephlegmator, continuously introducing raw oil to said dephlegmator, passing the uncondensed vapors to a condenser and receiver, and maintaining successively lower pressures upon the oil in the different parts of the system.

7. In a process for converting higher boiling point hydrocarbon oils into lower boiling point hydrocarbon oils, the improvement which comprises passing the oil in a plurality of substantially vertical streams first downwardly and then upwardly through a heating zone and raising the oil to cracking temperature during such downward and upward travel, discharging the heated oil into an enlarged zone wherein a separation of vapors and unvaporized oil occurs, removing vapors from said enlarged zone and subjecting the same to dephlegmation to condense therefrom the insufficiently cracked fractions, returning the condensed insufficiently cracked fractions to the heating zone for retreatment in the process, and condensing the dephlegmated vapors as the final product of the process.
